(57) **CLAIM**

I claim the ornamental design for a metal hardness test block with circular targets connected by alphanumeric grid lines, as shown in the accompanying drawings.

DESCRIPTION

FIG. 1 is an isometric view showing the top, right side, and front of the metal hardness test block with circular targets connected by alphanumeric grid lines.

FIG. 2 is a top plan view of the metal hardness test block circular targets connected by alphanumeric grid lines.

FIG. 3 is a bottom view of the metal hardness test block with circular targets connected by alphanumeric grid lines.

FIG. 4 is a left end view of the metal hardness test block with circular targets connected by alphanumeric grid lines.

FIG. 5 is a right end view of the metal hardness test block with circular targets connected by alphanumeric grid lines.

FIG. 6 is a front view of metal hardness test block with circular targets connected by alphanumeric grid lines; and, FIG. 7 is a rear view of the metal hardness test block with circular targets connected by alphanumeric grid lines.
